UNITED STATES PATENT OFFICE.

EARL R. COLLETT, OF PITTSBURGH, PENNSYLVANIA.

CUFF-BUTTON.

1,044,354.

Specification of Letters Patent.

Patented Nov. 12, 1912.

Application filed January 12, 1912. Serial No. 670,877.

To all whom it may concern:

Be it known that I, EARL R. COLLETT, a citizen of the United States, residing at Pittsburgh, in the county of Allegheny and 5 State of Pennsylvania, have invented new and useful Improvements in Cuff-Buttons, of which the following is a specification.

This invention relates to cuff buttons for link cuffs, the object of the invention being 10 to provide a button composed of two button members adapted to be easily and conveniently connected and disconnected by a relative endwise movement, to be pivotally coupled in such manner as to permit relative 15 movement of the meeting edges of the cuff without disconnection of said button members, and to adapt the latter to assume different relative angles of inclination to conform to variations in the form of the cuff, 20 and which when disconnected are adapted to securely retain their engagement with the edges of the cuff to which they are respectively applied, so that the cuff may be loosened and turned or folded back upon 25 the sleeve of the garment without liability of the button members dropping out and becoming lost or misplaced.

The invention consists of the features of construction, combination and arrangement 30 of parts, hereinafter fully described and claimed, reference being had to the accompanying drawing, in which:—

Figure 1 is a side elevation of a cuff fastener embodying my invention and showing 35 the parts connected. Fig. 2 is a longitudinal section through the same. Fig. 3 is a transverse section on the line 3—3 of Fig. 1. Fig. 4 is a perspective view of one of the members of the button or fastener. Fig. 5 is a 40 similar view of the other member thereof.

Referring to the drawing, 1 and 2 designate the two members or separable button elements of the fastener. The member 1 comprises a button or head 3 of suitable 45 form provided with a shank 4 carrying a ball or spherical portion 5. The member 2 comprises a button or head 6 having a pair of spaced jaws 7 projecting therefrom and made of spring or resilient material. The 50 said jaws 7 carry at their free ends a pair of socket members 8 adapted to receive the ball or spherical portion 5 of the member 1. The said socket members 8 are segmentally 55 cut away or recessed, as at 9, in their forward meeting edges to form a mouth or en-

trance having beveled surfaces, whereby the socket members are adapted to spring apart under pressure from the ball 5 to receive the same or to spring apart under a forward or lateral and forward pull upon said ball to 60 release the same.

It will be observed that the construction described provides a cuff button composed of two button members, each comprising an outer head, an inner head, and a connecting shank, whereby when said members are disconnected the cuff may be turned back upon the sleeve, for convenience in washing the hands, etc., without liability of said button members dropping out of the button holes 70 and becoming lost or mislaid, as the pair of heads upon each button member insure its firm retention upon the edge of the cuff to which it is applied. It will also be seen that the construction described permits the 75 two button members to be connected and disconnected in an easy and simple manner and by a relative endwise movement, thus enabling said members to be coupled or uncoupled without awkward or inconvenient 80 movements on the part of the wearer. It will further be seen that when the parts are connected, a relative universal motion is permitted, to adapt them to accommodate 85 themselves to the general movements of the cuff, while a pivotal movement is also afforded in the direction of the greatest width or major axis of the cuff by the construction of the shank 7 and socket elements 90 8 of the button member 2, which are spread by the head 5 of the button member, so as to provide intervening spaces or slots at diametrically opposite sides of the socket to permit the head 5 and its shank 4 to have 95 pivotal play so that the button members may freely assume different angular positions to accommodate themselves to the movements of the meeting edges of the cuff, without liability of said button members becoming separated.

Having thus described the invention, what I claim as new is:—

A cuff button for link cuffs comprising a pair of button members, one of said button members having an outer head of suitable 105 form, an inner head of spherical form, and a connecting shank, said inner head being of greater cross sectional area than said shank, and the other button part having an outer head of suitable form, a socket comprising 110

cup-shaped sections, and a connecting shank, said sections being relatively yieldable to receive and hold said spherical head and segmentally cut away at their forward edges and conjointly of greater cross sectional area than the respective shank, said button members being adapted for relative endwise connection and disconnection and for pivotal motion at an angle to the plane of open-

ing and closing movements of said socket sections.

In testimony whereof I affix my signature in presence of two witnesses.

EARL R. COLLETT.
